UNITED STATES PATENT OFFICE

167,880

STACKED SNACK JAR OR SIMILAR ARTICLE

Albert J. Dreitzer, New York, N. Y., assignor to Pitman-Dreitzer & Co. Inc., New York, N. Y., a corporation of New York

Application April 26, 1952, Serial No. 19,493

Term of patent 14 years

(Cl. D36—2)

To all whom it may concern:

Be it known that I, Albert J. Dreitzer, a citizen of the United States of America, and a resident of New York, in the county of New York and State of New York, have invented a Stacked Snack Jar or Similar Article, of which the following is the specification, reference being had to the accompanying drawings, forming a part hereof:

Figures 3 and 4 are top plan views of the sections below the lines 3—3 and 4—4, respectively, and

I claim:

The ornamental design for a stacked snack jar or similar article, substantially as shown.

ALBERT J. DREITZER.
